UNITED STATES PATENT OFFICE.

JOSEPH DE RUVO, OF NEW YORK, N. Y.

HAIR CURLER.

1,404,587.

Specification of Letters Patent. Patented Jan. 24, 1922.

Application filed March 23, 1921. Serial No. 434,798.

To all whom it may concern:

Be it known that I, JOSEPH DE RUVO, a citizen of the United States, and resident of the city of New York, borough of Manhattan, county of New York, and State of New York, have invented a new and Improved Hair Curler, of which the following is a full, clear, and exact description.

My invention relates to a hair curler and aims to provide certain new and useful improvements in connection with a device of this character.

It is well appreciated that numerous hair curlers have been placed upon the market, which include a sleeve heated by a resistance element, the hair being disposed within the sleeve for a certain length of time, and the heat acting to cause the hair to assume curls, or waves, in which they may have been disposed within the body of the curl.

Aside from the fact that these devices have been difficult in application, it is well understood by those conversant with their operation, that they have been inapplicable to a head of hair of relatively short length, and that in some instances, they have injured the hair.

With this in mind, I have provided a hair curler which may be utilized in connection with any length of hair, and by means of which a more natural wave and curl may be imparted to the hair, aside from the fact that the curler may be manufactured for a relatively small amount.

A further object of my invention is the construction of a device of the character stated which may more readily be associated with the hair, and by means of which any injury to the hair will be precluded.

Further objects of my invention will appear in the annexed specification and drawings, which latter present one practical embodiment of the same, and in which;

Figure 1 is a perspective view of my device and showing the same in use.

Figure 2 is an end view thereof.

Figure 3 is a side view of the same, and

Figure 4 is a sectional side view.

It will be noted, reference being had to the figures, that my invention contemplates, as its essential element, a sleeve composed of a pair of half sections 5 and 6, each of which preferably present metallic faces between which a suitable heat retaining filler encloses

a resistance element 7, it being noted in this connection that the outer layer of heat in-

sulating material 8 may be utilized to prevent outward radiation of the heat thus produced.

The sections 5 and 6 are hingedly secured one to the other, as has been indicated by the reference numeral 9, and a pair of arms 10 extend past the point of hinged connection 9, and have a spring 11 arranged between their bodies, which spring normally retains the sections 5 and 6 in the position indicated in the drawings.

A suitable source of electric supply may feed the resistance element 7 through wires 12, and it will be appreciated that the heat thus produced, will be transmitted to the arms 10. This would obviously render the manipulation of the device by the fingers of the operator impractical, and with a view of overcoming this objection it will be noted that I utilize a pair of heat insulating members 13, which are secured by means of resilient elements 14 to each of the arms 10. Thus it will be noted that an operator may effect an opening of the sleeve upon pressing the heat insulating members 13, and accordingly the arms 10, one towards the other.

In operation, it will be seen that the hair to be curled is wound around any desirable type of core element 15, subsequent to which the sleeve is opened in the manner stated, and caused to encircle the hair thus wound in the manner illustrated in Figure 1, it being noted that each of the sections 5 and 6 is formed with a notch 16, which presents in aggregate an annular opening suitable for the passage of the hair strands.

From the foregoing it will be seen that I have provided a hair curler, which will embody all of the benefits brought out in the preamble of this specification at the same time avoiding the objections therein noted, it being also appreciated that numerous modifications of structure might readily be resorted to without in the least departing from the spirit of my invention, which I claim as:

1. A hair curler, including a pair of sections, means for hingedly securing said sections one to the other, arms attached to said sections and extending beyond said point of hinging, and a spring interposed between the outer ends of said arms whereby to normally bring the outer edges of said coiler into contact with each other.

2. A hair curler, including a pair of sections, means for hingedly securing said sec-

tions one to the other, arms attached to said sections and extending beyond said point of hinging, a spring interposed between the outer ends of said arms, and a resilient element secured to each of said arms and a heat insulating member secured to the outer end of each of said elements.

3. A hair curler, including a pair of sections, means for hingedly securing said sections one to the other, each of said sections being formed with a notch in its side edges, presenting in aggregate an opening for the passage of hair strands, said sections each presenting a pair of spaced fastening members, a heat retaining material arranged be-

tween said members, and a resistance element disposed within said heat retaining material.

4. A hair curler, including a pair of sections, means for hingedly securing said sections one to the other, each of said sections being formed with a notch in its side edges, presenting in aggregate an opening for the passage of hair strands, said sections each presenting a pair of spaced fastening members, a heat retaining material arranged between said members, a resistance element disposed within said heat retaining material, and a layer of heat insulating material arranged beyond said heat retaining material.

JOSEPH DE RUVO.
